UNITED STATES PATENT OFFICE.

BANCROFT G. BRAINE, OF NEW YORK, AND JAMES G. DELFOX, OF FLUSHING, NEW YORK, ASSIGNORS TO THE RAIL JOINT COMPANY, OF NEW YORK, N. Y., A CORPORATION OF NEW YORK.

INTERLOCKED INSULATION FOR RAIL-JOINTS.

1,133,921.

Specification of Letters Patent.

Patented Mar. 30, 1915.

Application filed December 23, 1914. Serial No. 878,798.

To all whom it may concern:

Be it known that we, BANCROFT G. BRAINE and JAMES G. DELFOX, citizens of the United States, residing, respectively, at New York, county of New York and State of New York, and Flushing, in the county of Queens and State of New York, have invented certain new and useful Improvements in Interlocked Insulation for Rail-Joints, of which

10 the following is a specification.

This invention relates to sectional or divided insulation for rail joints, and has for its object to provide novel and practical means for maintaining the several pieces of insulation in proper insulating relation to the rails and splices. Accordingly, the present invention aims to simplify and improve the interlocking means for holding the insulating pieces or plates against relative 20 longitudinal movement, while not interfering with the ready removal and replacing of worn-out pieces of insulation without disturbing or affecting the remaining good or unworn insulation. Also, the improved construction is of such a character that a minimum amount of insulating material is employed to the best advantage both electrically and mechanically.

Another desirable object of the invention 30 is to provide novel means for locking the base insulation in position, and to impart thereto a pronounced resilient characteristic which will permit it to readily yield laterally when edgewise stress is placed thereon by the drawing in of the splice bars.

This action permits the splice bars to be properly fitted onto the rails without binding or interference from a rigid base insulation.

40 Other practical objects and advantages will appear to those familiar with the art as the details of the invention are better understood, and the latter consists in the novel construction, combination, and arrangement of parts hereinafter fully pointed out, illustrated, and claimed.

Though susceptible of a variety of structural modifications, and also applicable to different types of splices, certain preferred 50 and practical embodiments of the invention are illustrated in the accompanying drawings, in which—

Figure 1 is a perspective view of a rail joint embodying the present invention and

illustrating the three-piece insulation which 55 includes a head section, a rail flange section, and a base section or base plate. Fig. 2 is a detail perspective view of rail-head and rail-flange sections of insulation, constructed in accordance with the present invention, and shown in their interlocking relation to each other and to the joint bolts. Fig. 3 is a cross sectional view at the center of the joint shown in Fig. 1, illustrating the interlocking relation between the insulating 60 end post and the insulating base plate. Fig. 4 is a detail in perspective of the insulating base plate and the insulating end post, the parts being shown slightly separated to more clearly expose the keeper slot in the base 65 plate which receives the locking tenon on the end post. Fig. 5 is a side elevation of a modification of the invention, illustrating a different arrangement of the locking tongues on the insulating plates to prevent longitudinal movement thereof. Fig. 6 is a perspective view of another modification adapting the improvements for use in a one-end 70 insulating rail joint. Fig. 7 is a partial cross sectional view, at the center of the 75 joint, illustrating a modification wherein the base insulation for the rails is in the form of an insulating cuff fitting over the rail flange, but having the same interlocking 80 relation to the insulating end post as the single insulating base plate shown in Figs. 85 1, 3 and 4 of the drawings. Fig. 8 is a bottom plan view of the cuff form of base insulation showing the locking tenon of the 90 insulating end post engaged therewith.

Similar reference characters designate corresponding parts in the several figures of the drawings.

In carrying forward the present invention, the novel means employed for interlocking 95 the separate pieces of insulation are applicable to insulated rail joints of different design, and hence said means are available for use with any of the divers forms of splices which connect the rails and extend 100 across the joint between them, so that in any or all of its applications, the invention possesses the same utility and subserves the same functions.

A practical illustration of the invention 105 appears in Figs. 1, 2, 3 and 4 of the drawings. The rail joint shown therein includes the usual rails R, the joint bars or splices 1,

- 2
- and the usual joint bolts 2, which latter are insulated from the joint bars by any approved bolt insulating expedients, such as the insulating bushings 3 and washers 4.
- 5 The insulation for this joint comprises, in addition to the bolt insulation, an insulating end post 5 between the rail ends, an insulating head plate 6, and base insulation which preferably includes a separate insulating flange plate 7 overlying the rail flange and a separate insulating base plate 8 underlying the rail base. In this sectional insulation, the head plate is interposed between the under side of the rail head and the upper 10 edge of the joint bar, the said flange plate between the foot member 9 of the joint bar and the upper side of the rail flange, and the insulating base plate between the rail base and the rail supporting base member 10 of the joint bar. Accordingly, in a complete joint, of the kind shown, the base insulation comprises three separate pieces or sections, namely, the two flange plates at opposite sides of the rail, and the single base plate 8 15 underlying the rail base and substantially coextensive in area therewith. By thus dividing the insulation, the separate sections thereof are separately removable and replaceable so that worn out or damaged pieces 20 may be readily renewed without discarding the remaining good or unworn insulation.
- 25 As indicated, a primary and distinctive feature of the invention resides in providing simple and practical interlocking means for holding the separate insulating plates against relative longitudinal displacement or creeping. These interlocking means for the side insulation 6-7 include the joint bolts 2 and locking elements provided on the 30 insulating plates. For example, as clearly shown in Fig. 2 of the drawings, it is usual, in the "divided fiber" type of insulated rail joint, to employ a separate head plate or section 6 beneath the head of each rail, while 35 the base insulation may extend throughout the entire length of the joint, and these pieces of insulation are each provided with the locking elements referred to. That is to say, in the form of the invention referred to, 40 each insulating head plate 6 is provided at or adjacent its inner end with a single depending locking projection or tongue 11 adapted to extend into the space between the center pair of joint bolts and to have a shoulder engagement at one side of one of these 45 bolts. This construction and arrangement of parts disposes the locking projections or tongues 11 for both head plates 6 within the same space between the center pair of joint 50 bolts. Thus, each plate is prevented from longitudinal movement in one direction by engagement with one of the joint bolts, and from longitudinal movement in the opposite direction by engagement with the adjacent 55 end of the other head plate.

Corresponding means are provided to prevent relative longitudinal movement of the lower insulating plate 7 without any direct or indirect engagement between such plate and either of the head plates 6. This may 70 be accomplished by forming each insulating plate 7 with upwardly extending terminal locking projections or tongues 12, which are located at opposite extremities of the plate 7 and lie alongside of the rail web so as to 75 have a shoulder engagement with the terminal joint bolts. This construction and arrangement of the locking projections of tongues 12 disposes these elements in opposite and reversed relation, outside of the 80 bolts adjacent the ends of the joint, thereby securely locking each insulating plate 7 against longitudinal movement in either direction.

85 Provision is made for locking in place the insulating base plate 8 by a separable interlock with the insulating end post 5. This interlock is effected by constructing the insulating end post at its lower edge with a projecting locking tenon 13 which extends 90 below the rail base and engages in a keeper slot 14 piercing the base plate 8 at substantially the transverse center thereof. In addition thereto, the insulating base plate 8 is formed with a central longitudinally extending groove 15 which produces a downwardly dipping spring-bow lying in the interval between the inner spaced edges of the base members 10 of the opposite joint bars. 95 This detail of construction, in the insulating base plate, performs a useful function by imparting pronounced resiliency to the base plate so that it is capable of readily yielding to transverse stress imparted thereto. In 100 this connection, it will be observed that ordinarily when the joint bars are tightly drawn into place there may be instances in which the side edges of the insulating base plate rigidly contact with the closed ends α of the crotch γ of the joint bars, with the result of resisting a full inward movement for the joint bars, and consequently causing the bars to bind and their fit to be disturbed. 105 This condition is satisfactorily met by providing the base plate with the longitudinal spring-bow at the center thereof, said bow permitting the base plate to readily yield and contract laterally so that the joint bars or splices may at all times be tightly drawn 110 to a proper fit without interference from the insulating base plate.

115 By way of illustrating the range of modification that may be resorted to in carrying out the present invention, there is shown in Fig. 5 of the drawings, a form of construction wherein each insulating head plate 6 is provided with a centrally disposed downwardly projecting locking tongue 16 which enters into the space between a pair of the 120 joint bolts extending through the rail with 130

which the said plate is associated, while the lower piece or section of insulation, herein designated the insulating flange plate, is also shown as provided with a centrally located upwardly projecting locking tongue 17 which enters into the space between the central pair of joint bolts. In this form of construction, the insulating plates 6 and 7 are prevented from longitudinal movement in both directions by a shoulder engagement with the joint bolts, and without the interposition of direct or indirect locking means therebetween. Also, it will be understood that the improvements contemplated by the present invention are not to be limited to insulated rail joints wherein full insulation is provided for both rails. In other words, the invention is applicable to rail joints of the so-called one end insulated type. To illustrate the application of the invention to that type of joint, there is shown in Fig. 6 of the drawings, a modification wherein the insulating head plate 6 at each side of the joint is only fitted to one rail of the joint, while the other rail of the joint has fitted thereto a metal head-plate 18 of corresponding shape and dimensions. In this modification, the head plates 6 and 18 are shown provided with the same character and disposition of locking tongues 11^a as shown in Fig. 2 of the drawings, while the lower section or plate of insulation 7 may be provided with separate upwardly projecting locking tongues 19 which respectively project into the spaces between a pair of joint bolts through each of the rails. The functional effect of this construction and arrangement of parts is the same as already noted, namely to prevent longitudinal movement in either direction of the insulation plates.

A further modification of the invention that may be resorted to is shown in Figs. 7 and 8 of the drawings and consists in the employment of base insulation consisting of insulating cuffs 20 embracing the rail flanges, and formed at the transverse center of the base portions 21 thereof with transversely disposed keeper notches 22 to receive the downwardly projecting locking tenon 13 on the insulating end post. This form of construction is another example of the means contemplated by the present invention for locking the base insulation against movement by a separable interlock between the same and the insulating end post.

Other modifications, and other adaptations of the invention may obviously be resorted to, within the scope of the appended claims, without departing from the spirit or sacrificing any of the advantages of the invention.

We claim:

1. An insulated rail joint including sectional splice-bar insulation comprising an upper head plate having a depending lock-

ing tongue engaging between joint bolts, and a lower flange plate having an upstanding locking tongue engaging a joint bolt.

2. An insulated rail joint including sectional splice-bar insulation comprising an upper head plate provided with a depending locking tongue extending into the space between the central joint bolts, and a separate flange plate having a shoulder engagement with the terminal joint bolts. 75

3. An insulated rail joint including sectional splice-bar insulation comprising a head plate having a depending locking tongue extending into the space between the central joint bolts, and a separate flange plate provided at its ends with upstanding locking tongues having a shoulder engagement with the terminal joint bolts. 80

4. An insulated rail joint including sectional splice bar insulation comprising separate head plates, for the separate rails, each having a locking tongue projecting into the same space between a pair of joint bolts, and a separate flange plate provided at its ends with upwardly projecting locking 90 tongues overlapping the end joint bolts. 85

5. An insulated rail joint including sectional splice-bar insulation comprising separate head plates, for the separate rails, each having a locking tongue projecting into the space between the central joint bolts, and a separate flange plate provided at its ends with upwardly projecting locking 95 tongues overlapping the end joint bolts.

6. An insulated rail joint including sectional splice-bar insulation comprising separate head plates for the separate rails arranged in longitudinal alinement and provided at their inner ends with depending locking tongues projecting into the space 100 between the central pair of joint bolts, and a separate flange plate having a shoulder engagement with the bolts at opposite ends of the joint. 105

7. An insulated rail joint including sectional splice-bar insulation comprising a pair of upper head plates for the separate rails and provided at their inner adjacent ends with depending locking tongues projecting into the space between the central pair of joint bolts, and a lower flange plate provided at its ends with upwardly projecting locking 110 tongues overlapping the end joint bolts. 115

8. An insulated rail joint including sectional insulation comprising insulating head plates having locking projections interlocking with the joint bolts, separate flange plates arranged below the joint bolts and interlocking therewith, a separate insulating base plate underlying the rail base, and an insulating end post separably interlocked with the base plate. 120

9. An insulated rail joint including sectional insulation comprising insulating head 125

- plates interlocked with the joint bolts, separate base insulation including a section of insulation underlying the rail base and provided with a transversely disposed keeper slot therein, and an insulating end post having a locking tenon projecting into said keeper slot.
10. An insulated rail joint including sectional insulation comprising separate plates for the fishing spaces, a base plate provided with a central keeper slot, and an insulating end post having a bottom locking tenon separably interlocking with the slot of the base plate.
- 15 11. An insulated rail joint including a base plate unit provided with a spring portion to permit of yielding thereof under pressure.
12. An insulated rail joint including a base plate unit provided with a longitudinally extending spring portion to permit of yielding thereof under pressure.
- 20 13. An insulated rail joint including a base plate unit provided with a longitudinally extending groove forming a spring-bow to permit of yielding thereof under pressure.
- 25 14. An insulated rail joint including in combination with the rails and opposite rail base-supporting splices, an insulating base plate unit provided at an intermediate point with a longitudinally extending spring-bow disposed between the base members of said splices.
15. An insulated rail joint including sectional splice bar insulation comprising an upper head plate having a depending locking tongue engaging between joint bolts, and a lower flange plate having an upstanding locking tongue for engagement with a joint bolt.
16. An insulated rail joint including a section of insulation underlying the rail base, and provided with a keeper slot therein located beneath the rail base, and an insulating end post having a locking tenon projecting into said keeper slot.
- In testimony whereof, we hereunto affix our signatures in the presence of two witnesses.
